ANTIAIRCRAFT PROJECTILE AND FUSE FOR
SAID PROJECTILE

Robert Gourdon, Paris, France, assignor to Etablissements Edgar Brandt, Paris, France, a French company

Application July 23, 1947, Serial No. 762,973
In France July 29, 1946

10 Claims. (Cl. 102—70.2)

1

The present invention relates to anti-aircraft projectiles.

It is known that it is extremely difficult to obtain a direct hit on an aircraft moving at a very high speed, the path of which is always liable to sudden and unexpected variations.

Endeavours have been made to construct projectiles provided with very accurate time fuses which are intended to cause the shell to explode at a predetermined time after the shot has been fired; in spite of this, such projectiles are of very doubtful efficiency and involve a considerable waste of ammunition.

It has also been proposed to construct electronic fuses provided with ultra-short wave transmitting and receiving devices, but this type of fuse is fairly complicated and comparatively expensive to manufacture.

The present invention has for its object an antiaircraft projectile and a fuse which is extremely simple and easy to manufacture for said projectile and is based on an entirely different principle, said fuse being such that the projectile automatically bursts as soon as it is near the target.

Said projectile comprises, in combination, a metal body, an explosive charge in said body, and at the front of said body a fuse which is adapted to ignite said explosive charge by the action of the discharge, i. e. the flow, through said fuse and said body, of a portion of the electrostatic charge which has accumulated on the target, said projectile, when it is adjacent to said target and owing to its high speed of translation and rotation, producing a preferential path (i. e. a path of lower ohmic resistance than that of all the other possible surrounding paths) which is followed by said electrostatic charge of the target in order to reach a region of the atmosphere at lower potential.

It is in fact known that a moving body such as an aircraft, moving at high speed through the equipotential layers of the atmosphere, becomes charged at a higher potential than that of the equipotential layer through which it is moving. After saturation, the charge thus accumulated on said aircraft flows away slowly and continuously towards the ground. The tapering shapes of the wings of the aircraft and of the elevator and rudder, contribute to this leakage towards the lower layers at lower potential.

Under these conditions, if another moving body, such as a projectile, is fired obliquely upwards in the direction of the aircraft, it produces an oblique disturbance in the atmosphere. The disturbance

2

of the layers of air through which it passes is greater as the translational and rotational speeds of the projectile are higher and a considerable ionization is thereby produced in the immediate vicinity of said projectile and chiefly behind it. This ionization is due, on the one hand to the direct impact on the air and the particles in suspension which are encountered, and on the other hand to the vortex that the projectile forms behind it. The ohmic resistance of the surrounding layers through which the projectile passes is therefore substantially changed and a highly ionized preferential discharge path of a certain length is thus formed which is a better conductor than the surrounding air that has remained calm between the surrounding equipotential layers; it is along this preferential path, the ohmic resistance of which is decreased owing to the presence of the projectile and to the ionization which it produces behind it, that a portion of the electrostatic charge accumulated on the surfaces of the aircraft flows.

The ionized path comprises the nose of the fuse, the body of the projectile and its disturbed wake. The projectile according to the invention makes use of the quantity of electricity which is supplied by the target and which flows along said path and supplies the necessary energy to produce a spark without it being necessary to have recourse either to a special source of electric power contained in the projectile, or to a capacity and electrostatic discharge effect of said projectile.

The invention also has for its object a fuse intended for said projectile. Said fuse comprises, in combination, a detonator, a primer located adjacent to said detonator, means for producing through said fuse a path of lower electric resistance than that of the surrounding portions for the discharge of a portion of the electricity accumulated on the target opposite the projectile when said projectile is near said target, and means for igniting said primer by means of said discharge.

With such a device, the ignition occurs automatically as soon as the projectile is sufficiently close to the target for the electric discharge of the static electricity of the target to take place through said fuse; the projectile therefore does not have to come into contact with the target in order to explode; on the other hand, when it explodes, it is at a suitable distance from the target for the effect of the explosion and of the projection of splinters to be effective.

The invention also has for its object a projectile of the aforesaid type, wherein the fuse is

protected, before the projectile is fired, from any untimely electric discharge through it my means adapted to be eliminated when the shot is fired, for example by centrifugal effect, since it is essential for such a projectile to be provided with a safety device that protects it from any accident that could be caused by atmospheric discharges, the proximity of high tension electric lines, electric motors in operation, and the like.

Other features and advantages will become apparent from the ensuing description.

In the accompanying drawing which is given solely by way of example:

Fig. 1 is an axial section of a projectile fuse according to the invention;

Fig. 2 shows a partial axial section, on its trajectory, of a projectile containing a tracer charge;

Fig. 3 shows diagrammatically the path followed by the electrostatic discharge when a projectile of the type shown in Fig. 2 is close to the target;

Fig. 4 is a fragmentary section of a modification.

According to the embodiment shown in Fig. 1, the fuse comprises a fuse body 1 in which is fitted, by moulding or otherwise, an insulating portion 2 forming the front part of the fuse. The body 1 and the insulating portion 2 which are closely secured together are of ogival external shape.

The insulating portion 2 surrounds a filiform axial electrode 3 which is a very good conductor. Said electrode, which is flush with the front face of said portion 2, may for example be made of electrolytic copper; its diameter is of the order of a few tenths of a millimetre and it has no apparent capacity.

A very thin cover 4, preferably formed of a fine sheet of tin, completely covers the ogive in order to protect the fuse from any untimely discharge of electricity through said fuse, until the instant when the projectile leaves the gun, said sheet of tin being sufficiently thin to be eliminated, when the shot is fired, for example merely by the effect of the centrifugal force.

A primer 5 is housed in an insulating cup 6 which is preferably made of compressed material. Said cup is in turn fitted in the rear section of the insulating portion 2. The primer 5, which does not contain any extra-sensitive substance (lead nitride) contains a small percentage of mercury fulminate (about 38%) and substances capable of effecting the division, the oxidation or the binding of the compound (about 10 to 20% of calcium silicide; about 30 to 40% of barium nitrate; about 7 to 10% of lead peroxide).

This compound is insensitive to mechanical shocks such as might be caused by crushing the nose of the fuse; it is such that its ignition is produced by a sort of chain reaction of the mercury fulminate crystals which are isolated from one another by the calcium silicide, at least one of said crystals being ignited by the calorific and/or electronic effect of a spark produced by a potential difference of a few thousand volts and a weak current of the order of one microampere.

The rear end of the axial electrode 3 is kept at a very short distance e from the primer 5 by the thickness of the cup 6 which is provided with a central hole 7, thereby breaking the circuit at this point. This gap does not exceed a few tenths of a millimetre.

Behind the primer 5 is arranged a thin sheet

8 for example of tin, which is held in position by a detonator-holder 9 screwed at 10 in the body 1. The charge 11 of this detonator is supported by a diaphragm 12 provided with a central hole 13 which is intended to transmit the fire.

The projectile 14 shown in Fig. 2 on its trajectory comprises a fuse such as hereinbefore described. The rear portion of the detonator is housed in the mass of explosive 15. This projectile, which has been fired from a rifled gun, as is proved by the fact that it is provided with a rifling-band 16, contains a tracer charge 17 housed in the rear portion 18 of the projectile.

15 The whole arrangement operates as follows:

When the shot is fired, the cover 4 of the fuse is torn off by the effect of the centrifugal force due to the rotation which the projectile undergoes on its trajectory. The thin sheet 8 keeps the primer 5 in its compact shape and prevents it from penetrating by inertia into the hole 13. The very fast rotation and also the high speed of translation of the projectile as it rises obliquely into the atmosphere causes a disturbance 19 (Fig. 25) behind said projectile and, after a certain altitude, said disturbance produces a highly ionized path over a distance which connects together layers of air, the potential difference $V_n - V_1$ (Fig. 3) of which may reach several thousand volts. It should be noted that the distance 30 between the two layers V_n and V_1 need not be large, since the operation of the fuse is produced by a potential difference of a few thousand volts on either side of the spark gap 15.

35 This ionization of the trajectory behind the projectile is further increased in the case in which the projectile is provided with a tracer charge 17, the combustion of which has the effect of projecting metal particles 20 (Fig. 2) along 40 said trajectory.

When the projectile approaches the target 21 (aircraft) (Figs. 2 and 3), the electrostatic charge which has accumulated on said target as it moves at high speed through the equipotential layers 45 of the atmosphere is displaced in the direction of the projectile and accumulates on an area 22 of high surface density. The charge voltage on the surface 22 is much higher than that of the equipotential layer through which the aircraft is moving owing to the speed of said aircraft and 50 the accumulation of ions caused thereby. Said charge is in any case higher than that which can be collected by the projectile of much smaller size which is moving towards it and is passing through the same ionized layer.

55 Consequently, as soon as the projectile is at a distance from the target equal to or shorter than a certain distance a (Fig. 3) a leakage of the electrostatic charge takes place along the lines 23 from the surface 22 towards the preferential path, i. e. the path of least ohmic resistance, formed by the projectile itself and its highly ionized wake 19, the ionization being further increased by the metal particles 20. Said leakage is concentrated 60 towards the tip of the ogive of the projectile.

Almost the entire charge of electricity, in the form of a brush discharge, follows the path of the central electrode 3 which is well insulated and which, since it is preferably of electrolytic copper, 65 is of much higher conductivity than the surrounding medium, while its capacity, which has absolutely no function to perform herein, is nearly nil since said electrode is as short as possible.

Owing to the gap of width e that exists at 70 75 (Fig. 1), all the energy of the discharge is con-

centrated and discharged in the form of a spark of very low intensity (a few microamperes) through the extra-sensitive priming compound forming the primer 5. Said energy, which corresponds to a potential difference of several thousand volts, i. e. to the potential difference between the target and the rear of the projectile, is therefore partly converted into heat energy before it flows through the projectile and the ionized wake thereof towards the lower potential layers.

The heat energy produced by the disruptive spark and the electronic impact on the crystals of the primer 5 ignites said primer which fires the charge 11 of the detonator through the opening 13 and causes the projectile 14 to explode without said projectile needing to come into contact with the target.

It should be noted that experiments have proved that the fuse is practically insensitive to an impact; it may for example pass through a hard obstacle without operating, since either the electrode 3 merely buckles, i. e. becomes curved, or it comes into contact with the primer at a considerably reduced speed such that, taking into account the relative mechanical inertia of the primer, the same does not operate.

Furthermore, it is possible to adopt the arrangement shown in Fig. 4, wherein the electrode 3 is bent for example twice symmetrically with respect to the axis at 3^a and 3^b, so that an accidental impact that produces a considerable deformation of the nose of the fuse merely deforms the bends 3^a and 3^b, thereby avoiding a mechanical transmission of the stress from the electrode 3 to the primer 5.

Naturally, the invention is in no way limited to the embodiments illustrated and described which have only been chosen by way of example. Thus the filiform electrode 3 of the foregoing examples may be replaced by a conducting substance, for example in powdered form, filling an axial duct provided in the insulating member 2.

Having now described my invention, what I claim as new and desire to secure by Letters Patent is:

1. An anti-aircraft projectile, comprising in combination a hollow metal body, an explosive charge in said body, and at least one fuse projecting from said body and comprising a dielectric mass forming a front nose that projects from the body of the projectile, at least one electric conducting element which has practically no capacity and which passes from end to end through said dielectric mass and terminates at the surface thereof by its forward end, a primer located at least adjacent to the other end of said conducting element, means for igniting said primer by the action of the flow of an electric

current through said conducting element and said projectile, and a detonator located adjacent to said primer.

2. An anti-aircraft projectile according to claim 1, furthermore comprising, at the rear of said hollow body, a tracer charge with metallic particles for increasing the ionization of the atmosphere in the wake of said projectile.

3. A fuse for an anti-aircraft projectile, comprising in combination, a metal body, a dielectric mass housed in said body and forming a projecting front nose, at least one electrode extending through said dielectric mass and terminating at one of its ends on the outer surface of said mass, a primer located at least adjacent to the rear end of said electrode, means for igniting said primer by the action of a flow of electricity through said electrode and said projectile, and a detonator mounted in said body behind said primer.

4. Fuse according to claim 3, wherein said means for igniting said primer comprise a small spark gap provided between the rear end of said electrode and said primer which is sensitive to the electronic impact and to the heat which are produced by an electric discharge passing across said gap.

5. Fuse according to claim 3, wherein said electrode is filiform and is of very low electrostatic capacity.

6. Fuse according to claim 5, wherein said electrode is made of electrolytic copper of high conductivity.

7. Fuse according to claim 3, wherein said electrode is filiform and has at least one bend therein so that an impact will cause it to yield and thereby prevent a mechanical ignition of the primer.

8. Fuse according to claim 3, wherein said primer is of a composition which is insensitive to a physical percussion produced by said electrode.

9. Fuse according to claim 3, furthermore comprising means for protecting it from any untimely electric discharge before it is fired.

10. Fuse according to claim 9, wherein said protecting means comprise a metal cover adapted to cover the front portion of said fuse and to be eliminated as the projectile leaves the barrel of the gun.
